CLAIM

The ornamental design for a fishing lure, as shown and described.

DESCRIPTION

FIG. 1 is a side elevational view of a fishing lure showing my new design, the side not shown being identical to the side shown;

FIG. 2 is a perspective view of the fishing lure;
FIG. 3 is a top plan view of the fishing lure;
FIG. 4 is a rear elevational view of the fishing lure; and,
FIG. 5 is a front elevational view of the fishing lure.
